(57) CLAIM

The ornamental design for a headwear as shown and described.

DESCRIPTION

FIG. 1 is a perspective view of the headwear showing our new design;

FIG. 2 is a front elevation view thereof;

FIG. 3 is a rear elevation view thereof, depicting a zipper to allow for bump cap insertion;

FIG. 4 is a right side elevation view thereof;

FIG. 5 is a left side elevation view thereof;

FIG. 6 is a top plan view thereof; and,

FIG. 7 is a bottom plan view thereof.

The broken lines included in FIG. 1 are for the purpose of illustrating environmental structure and form no part of the claimed design.

1 Claim, 7 Drawing Sheets
